Primary Examiner — Cary M Robinson*Assistant Examiner* — Emily Anna Saunders(74) *Attorney, Agent, or Firm* — Jose Cherson Weissbrot(57) **CLAIM**

The ornamental design for a toy bubble gun, as shown and described.

DESCRIPTION

FIG. 1 is a front, top, right side perspective view of the toy bubble gun, showing my new design;

FIG. 2 is a back, rear, left side perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the area labeled 9 in FIG. 1; and,

FIG. 10 is an enlarged view of the area labeled 10 in FIG. 2.

The broken lines shown in the drawings depict portions of the toy bubble gun that form no part of the claimed design. The dot-dash broken lines encircling portions of the toy bubble gun in FIGS. 1 and 2 and illustrated in enlarged views in FIGS. 9 and 10 form no part of the claimed design.
